UNITED STATES PATENT OFFICE.

SAMUEL P. KITTLE, OF BUFFALO, NEW YORK.

DOOR-FASTENER.

Specification of Letters Patent No. 9,765, dated June 7, 1853.

To all whom it may concern:

Be it known that I, SAMUEL P. KITTLE, of Buffalo, in the county of Erie and State of New York, have invented a new and improved mode of fastening or locking doors so that they cannot be opened or unlocked from the outside, which I term a "traveling lock"; and I do hereby declare that the following is a full and exact description thereof, reference being had to the accompanying drawings and to the letters of reference marked thereon.

The nature of my invention consists in providing the door rabbet with a metal bar sufficiently thin to allow the door to shut. Said bar is of stiff metal and provided with an edge or edges, spur or spurs at one end, which edge or edges spur or spurs are pressed into the wood forming the rabbet by closing the door or otherwise, and the said edges or spurs are prevented loosing their hold in the wood by means of the edge of the door resting against the bar or a cap which is used in connection with the bar when the door fits badly. The other end of said bar which projects beyond the face of the door when closed is provided with a stop or rest which when the door has been closed as above is made to bear as on the face of the door, thus securing it so long as the edges or spurs do retain their hold in the rabbet.

To represent and set forth more clearly the nature of my invention, I will proceed to describe its construction and operation.

I construct my traveler's lock of any metal or composition that does not bend or break easily.

Figure 1 is a perspective view of the lock closed with the edges up, exposed to view. Fig. 2 is a perspective view of the lock open with cap on. Fig. 3 represents the application of the lock in a section of a door and casement which are cut through the center of the lock.

Let the same letters represent the same parts in the above figures, then A will represent the bar or strap; B the stop or rest; C the brace or guide, and D the cap. There are no necessary exact dimensions for either of these parts, provided all agree together, but it is found convenient to make the bar A $2\frac{1}{2}$ inches long, $1\frac{1}{4}$ inches wide, and $\frac{1}{8}$ of an inch or less thick, with the end that is to be inserted between the edge of the door and face of the rabbet bent back at an angle

of about ninety degrees from a line with the face of the bar to form the edge or edges E, E, as seen, or it may be made one continuus edge, or cut into numerous pricks like saw-teeth, or there may be spurs set into the bar, or there may be a separate plate with similar device made so as to admit of a connection with the bar A, any of which would not materially alter the principle or design of the lock.

I, I, on the bar in Fig. 2 represent gains in the edges of the bar when the cap D is put on or taken off. The end of the bar A which projects beyond the rabbet and face of the door when closed must be provided with a stop or rest which is or can be connected with the bar A and made to bear on the face of the door when closed. This it is found convenient to do by the rivet H, which when used will secure together the bar A, the stop B, and the brace C, and allow either or both the stop and brace to be thrown around back as seen in Fig. 2, or in place of the rivet the bar and stop may be hinged together or connected by ratchet and spring or screw or in any way that will allow the stop to be taken off or thrown back to admit the door. The stop B may be made of like material and same width and thickness of the bar A. The brace or guide C, as seen, is of like material with the bar A and secured to it by the rivet H, the lip G which is formed by bending the end of the brace so that it will stand when closed at about a right angle with the back of the bar A. The brace C acts as a guide in setting the lock into the rabbet and is also a brace to strengthen the bar A. The lip F as seen can be formed on the stop B by tending the material either out or in so that it will stand at about a right angle with the face of the bar A when closed as seen in Fig. 1, and as shown in Fig. 3. This mode saves unnecessary metal and bulk. This lip should be of circular form the rivet being the center when used as here represented, so that after the spurs have been secured in the rabbet and the door closed the stop B may be brought around and pressed upon the face of the door, securing it closely.

The cap D, as seen in Fig. 2, is simply a piece of metal of wedge form to be used when the door does not fit closely into the rabbet as shown in Fig. 3. This cap may be connected with the bar A in various ways. It has been found convenient to do this by

lips J, J, as seen in Fig. 2. These lips are simply bent over the edge of the bar A or made to fit it so that the cap may be taken off at I, I, when not required.

5. What I claim as my invention and desire to secure by Letters Patent is+

1. The combination of the bar A having the edges E, E, with the stop or rest B, having the lips F and G constructed and arranged as described.
10. 2. I further claim the combination of the

cap D with the bar A, the effect of the cap being to fill up the space between the edge of the door when closed and the casing as described, all for the purposes and con- 15 structed in the manner substantially as set forth in the accompanying specifications and drawings.
